(57) **CLAIM**

The ornamental design for a beverage insulation sleeve storage and dispenser device with top weight, as shown and described.

DESCRIPTION

FIG. 1 is a front perspective view of the beverage insulation sleeve storage and dispenser device with top weight;

FIG. 2 is a front elevational view thereof;

FIG. 3 is a back elevational view thereof;

FIG. 4 is a left-side elevational view thereof;

FIG. 5 is a right-side elevational view thereof;

FIG. 6 is a top plan view thereof;

FIG. 7 is a bottom plan view thereof showing the design in use with a beverage insulation sleeve stored therein; and, FIG. 8 is a left-side elevational view thereof showing the design mounted on the outside of a cabinet.

The dash-dash broken lines in FIG. 6 showing a top weight and in FIG. 7 showing a beverage insulated sleeve depict environmental subject matter that forms no part of the claimed design. The dash-dot broken lines in FIG. 8 showing a cabinet depict environmental subject matter that forms no part of the claimed design. The remaining dash-dot broken lines in FIG. 8 depict view boundary limits that form no part of the claimed design.
